UNITED STATES PATENT OFFICE

2,518,343

LUNCH BOX

Arnold O. Lindstrom, Republic, Wash.

Application November 7, 1947, Serial No. 784,637

1 Claim. (Cl. 220—8)

1

This invention relates to a lunch box and it is one object of the invention to provide a lunch box, comprising a body having associated therewith, a lower section constituting a bottom for the body and having telescoping engagement with the body, so that it may be shifted vertically to adjusted positions and thus increase the capacity of the lunch box which, when empty, may be reduced to its normal size and conveniently carried by a person.

Another object of the invention is to provide a lunch box wherein, an auxiliary lower section fits into the body of the box through the open lower end thereof, and carries arms movable into and out of position for engaging selected ones of vertically spaced stops projecting inwardly from walls of the body and thus allowing the depth of the lunch box to be progressively increased and the lower section firmly held in its adjusted position.

Another object of the invention is to provide the lunch box with an adjustable lower section carrying a plurality of securing members, which are formed of resilient metal and are simultaneously moved to a retracted position by a single adjusting member having cams for engaging both of the securing members.

Another object of the invention is to provide the lunch box with a dome-shaped cover having improved means carried thereby for securing a vacuum bottle in the cover.

Another object of the invention is to provide an improved latch for releasably securing the cover closed.

Another object of the invention is to provide a lunch box having an auxiliary lower section for its body which may be entirely removed therefrom, and the body and its lower section thoroughly cleaned after use.

The invention is illustrated in the accompanying drawings wherein:

Fig. 1 is a perspective view of the improved lunch box, the extended position of its lower section being indicated by dotted lines.

Fig. 2 is a sectional view upon an enlarged scale taken transversely through the lunch box along the line 2—2 of Figure 1.

Fig. 3 is a fragmentary sectional view taken vertically along the line 3—3 of Figure 2, the extended position of its lower section being indicated by dotted lines.

Fig. 4 is a perspective view showing the securing means for holding the lower section of the lunch box in an adjusted position.

Fig. 5 is a perspective view of the means for securing a vacuum bottle in the cover of the lunch box.

Fig. 6 is a view taken vertically along the line 6—6 of Figure 2 upon an enlarged scale and showing the latch for holding the cover of the lunch box closed partially in section and partially in elevation.

2 This improved lunch box has a body 1, which is preferably formed of sheet metal but may be formed of other suitable materials. This body is open at its top and its bottom and has end walls 5 and 2, and front and rear side walls 3 and 4. Upper portions of the side and end walls of the body are offset inwardly to reduce the dimensions of the upper end of the body and allow a cover 5 connected with the rear wall 3, by hinges 6, to be easily moved into position for closing the upper end or top of the body 1. A handle 7 is provided upon the cover for carrying the lunch box and in order to releasably secure the cover closed there has been provided a latch 8 carried by the cover and movable into and out of engagement with a keeper 9 carried by the front wall 4.

An auxiliary lower section 10 is associated with the body 1 and has a bottom 11 and side walls 12 and end walls 13, the lower section being of such dimensions that its walls will fit snugly within the body and thus establish telescoping engagement between the body and the auxiliary lower section. A handle 14 is connected with the bottom 11 by hinges 15 and is normally secured in a folded position against the bottom by a latch 16 from which it is readily detachable when it is to be swung downwardly into position to be grasped and the lower section drawn downwardly to an extended position for increasing the depth of the lunch box. Bosses 17 which are struck downwardly from the bottom 11 are provided so that when the lunch box is set upon a shelf or table it will rest upon these bosses instead of upon the folded handle 14.

35 Normally the lower section 10 is in a retracted position within the body and in order to allow this lower section to be releasably secured in its retracted position and also in an extended position, there have been provided securing arms 18 formed from strips of resilient metal. These metal strips have their lower portions bent to form feet 19, which are welded to each of the end walls 13, of the lower section, and referring to Figures 2, 3 and 4 of the drawings, it will be seen that the companion securing arms are spaced from each other transversely of the walls to which they are secured and extend vertically with their upper portions projecting above the wall and bent at their upper ends to form bills 19' which project outwardly from the walls of the auxiliary section. Bars 20 are mounted vertically against inner surfaces of the end walls 2 of the body 1 and these bars are formed from metal strips which are crimped to form abutment ribs 21, spaced vertically from each other. When the bills 19' of the arms or latches 18 are engaged over the ribs at upper ends of the bars 20, the auxiliary lower section of the body will be held in a retracted position which is its normal position and when the bills are engaged with selected ones of the other ribs the auxiliary section will be supported in a lowered or extended position.

in which it projects from the body a predetermined distance and transform the lunch box from a normal depth to a desired depth for accommodating an increased quantity of food. It will thus be seen that the lunch box may be adjusted for depth, according to the quantity of food to be packed in it, and that after the food has been removed from the lunch box and eaten the auxiliary section may be returned to its retracted position and the lunch box readily carried or stored in a kitchen cabinet or table drawer without occupying too much room therein.

In order to shift the bills out of engagement with the flanges or ribs of the bars 20, each end wall of the auxiliary section carries a rod shaft 22 which is rotatably mounted through a bearing 23, welded to and extending transversely of the wall. End portions of the shaft 22 are flattened to form cams 24 which extend between the wall 13 and the arms, and when the handle 25 is grasped and swung upwardly the shaft will be rotated and the cams moved from a position flat against the inner surface of the wall 13 to an extended position in which they project from this wall and have pressing engagement with the arms. During this turning movement of the shaft and the cams carried thereby both of the arms will be flexed away from the wall 13 and out of overlapping engagement with the flanges or ribs of the bars or keeper strips 20 and the auxiliary section will then be free to move vertically and may be shifted to a position in which it projects downwardly from the body a desired distance, at which time the handle will be thrust downwardly until it again bears against the inner surface of the end wall of the auxiliary section and the cams return to the initial position which allows the arms to spring outwardly and overlap a lower set of ribs or flanges of the bar and very effectively support the auxiliary section in an extended position. After food in the lunch box has been removed the cams will be again operated to swing the arms or latches to a releasing position for allowing the auxiliary section to be shifted upwardly to its normally retracted position and the cams then moved to their normal position for allowing return of the arms into operative position.

In order to hold a vacuum bottle 26 in the dome-shaped cover there have been provided straps 27 and 28 which are formed of metal strips and extend transversely of the cover, ends of the straps being pivoted to the cover, as shown at 29. A bill or tongue 30 is pivoted to the free end of the strap 27, as shown at 30'; and to the free end of the strap 28 is pivoted a metal loop 31. A tooth or finger 32 which is struck from the bill 30, projects outwardly therefrom, the bill is so curved longitudinally that when the tooth is engaged through the outer end of the loop and the bill swung towards a position in which it bears against the strap 27, a portion of the bill will pass through the loop and pull will be exerted upon the loop by the tooth to draw the straps into tight gripping engagement with the vacuum bottle. Since the loop passes a dead center as it is drawn towards the securing position it will be held in this position and can not accidentally swing towards a releasing position and allow the vacuum bottle to drop out of the cover.

The latch 8 by means of which the cover is releasably held closed is illustrated in Figure 6 and consists of a metal strand bent to a U-shape in order to provide arms 33 and 34 connected by a bridge 35. The arm 33 is slidably and rotatably

mounted through a sleeve 36 serving as a bearing for the latch, and having one end formed with a head 37 through which the arm passes. A spring 38 surrounds the arm 33 within the sleeve, and has one end in engagement with the head 37 and its other end engaging a washer 39, which is held to the arm by a screw 40 and forms a head for this arm. Resiliency of the spring normally holds the latch in a retracted position in which the arm 34 is engaged in the keeper sleeve 9 and the cover will be held closed, but when the latch is grasped by its bridge 35 and pull exerted to draw the arm 33 longitudinally through the bearing sleeve 36, the arm 34, which is shorter than the arm 33, will be withdrawn from the keeper and the latch may then be used as a handle for swinging the cover upwardly to an opened position. When the cover is closed the latch is again grasped by its bridge and drawn outwardly to an extended position which allows the free end of the arm 34 to be disposed opposite the end of the sleeve 9 and upon releasing pulling force upon the latch, the spring will shift the latch to its retracted position and cause the arm 34 to enter the keeper sleeve and securely hold the cover closed.

Having thus described the invention, what is claimed is:

A lunch box, comprising a body open at its top and bottom, a cover for said body, an auxiliary section in said body shiftable vertically through the open bottom of the body from a normally retracted position to a downwardly extended position for increasing the depth of the lunch box, resilient arms mounted vertically against the inner surface of an end wall of the auxiliary section and spaced from each other transversely thereof, said arms having upper portions projecting upwardly above the said auxiliary section and provided with outstanding bills overhanging the upper edge of the said end wall, bars mounted vertically against the inner surface of a confronting end wall of the body and crimped to form transversely extending vertically spaced ribs for overlapped engagement by the bills to support the auxiliary section in retracted and extended positions, a bearing mounted horizontally upon the inner surface of the said wall of the auxiliary section between said arms, a rod rotatably mounted horizontally through said bearing and having its end portions formed with cams across which said arms extend, and a handle carried by said rod for rotating the rod and turning the cams away from the wall of the auxiliary section into position to flex the arms out of position for engagement with the ribs and allow vertical shifting of the auxiliary section.
